CLAIM

The ornamental design for a clip of bicycle pedal, as shown and described.

DESCRIPTION

FIG. 1 is a front perspective view of a clip of bicycle pedal, showing my new design;

FIG. 2 is a rear perspective view thereof;

FIG. 3 is a front perspective view showing the clip in the context of a pedal;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view.

The broken lines in the drawings illustrate the portions of the clip of bicycle pedal, which form no part of the claimed design.

1 Claim, 9 Drawing Sheets
